AUTOMATIC RECLOSED SYSTEM FOR ELECTRIC SWITCHES

Application filed November 20, 1923. Serial No. 675,964.

This invention relates to electric switches, and apparatus and systems for automatically controlling electric switches; and has particular reference to automatic reclosing means for electric switches.

In certain types of electrical distribution systems, an electric switch controlling a particular circuit may be provided with means to effect the automatic reclosing of the switch when the switch is opened automatically by reason of an overload in its circuit. The reclosing means may also be arranged to reclose the switch a certain predetermined number of times upon its overload opening and if the switch again opens because of the persistence of the overload, the reclosing means may then be conditioned to permit the switch to remain open.

An object of this invention is to provide an automatic reclosing system wherein the number of reclosings of the switch upon overload may be varied to suit various conditions of the distribution system; and also wherein the time intervening between the overload opening and the subsequent reclosing of the switch may be varied.

A further object is generally to improve the construction and operation of automatic reclosing apparatus and systems.

Fig. 1 is a schematic representation of the automatic reclosing system and apparatus embodying the invention.

Fig. 2 is a side elevation of a control relay associated with the system.

Fig. 3 is a front elevation in detail of the speed-reducing and circuit-controlling mechanism of Fig. 1.

As here shown, the electric switch associated with the invention and adapted to be opened upon overload and repeatedly closed may comprise a three-phase switch 10, which switch is adapted to control the circuit 11. Said switch may be provided with operating mechanism which may include the tripping or opening coil 12 and the closing coil 13. An auxiliary switch 14 is associated with the main switch 10 and is adapted to be moved in one direction when the main switch is closed and moved in the opposite direction when the main switch is opened.

Said auxiliary switch may comprise a plurality of movable or bridging contact members 15, 16, 17, and 18 and said bridging members are adapted to engage and bridge the pairs of stationary contact-members 19 through 26 inclusive. When the auxiliary switch is moved in one direction, said bridging members are adapted to engage and electrically bridge the upper pairs of contacts and when said movable member is moved in the opposite direction, said bridging members are adapted to engage and electrically bridge the lower pairs of contacts. Bridging member 15 for instance, when moved into an upper position, corresponding to the closed position of the main switch 10, is adapted to engage the upper pair of fixed contact-members 20. When said bridging member is moved into a lower position, corresponding with the open position of the main switch 10, said bridging member is adapted to engage the lower set of contact-members 19. The same may be true in connection with the remaining bridging members.

Power for energizing the opening and closing coils may be taken from the auxiliary power buses 30 and 31. When an overload occurs in the line 11, the current transformers 32 may be energized sufficiently to actuate the overload relays 33 and said relays may serve to complete the circuit through the fixed relay contacts 34 and the opening coil 12, the current passing from the auxiliary bus 30 through the conductor 35, the opening coil 12, the conductors 36, 37 and 38, the relay contacts 34 and the conductor 39 to the other auxiliary bus 31. The switch 10 may also be opened manually by means including the manually-controlled switch 40. Said switch 40, when actuated, serves to bridge or shunt the overload relay contacts 34 and complete the circuit between the auxiliary buses and the opening coil 12. The main switch 10 may also be opened upon a reduced potential in the line 11 by means of the undervoltage relay 42, the plunger 43 of which falls upon reduction of potential and bridges its contacts and thereby completes a circuit through the opening coil 12, the current passing from the conductor 36 through the auxil-

ary switch contacts 20 and bridging member 15 to conductor 45 and thence to the auxiliary bus 31. When the main switch 10 is in open position it may be closed manually by means including the closing switch 47 and when said switch is closed, the current passes from the auxiliary bus 30 through the hesitating relay 48 and conductors 49 and 50, through the fixed contacts of the closing switch 47 and conductor 51 to the other auxiliary bus 31. The hesitating relay is thereby energized to bridge its contacts 52 and complete the circuit including the closing coil from the bus 30 through the conductor 53 and conductor 45 to the other auxiliary bus 31. The control system for the switch as so far described may be more or less common in the art.

In accordance with this invention, I provide means, as a reclosing relay, arranged repeatedly to close the main switch 10 after it has been opened repeatedly by overload. Said relay may also be provided with means to vary the time period intervening between closing operations. I may also provide other means, as a disconnecting relay, to govern said reclosing relay and the number of operations thereof and thereby time the number of reclosings of the main switch 10. Both the reclosing and disconnecting relays may be similar in construction and the construction thereof may be as illustrated in Figs. 2 and 3. As shown in these figures, the relay may comprise essentially an electric motor having the frame 60 in which the armature 61 is rotatably supported. The motor may also include an upper and fixed pole piece 62 which may be energized by the field coil, or actuating coil, 63. A second field pole 64 may be pivotally connected with the frame 60 and may be energized by a separate field coil, or resetting coil, 65. A spring 66 may serve to maintain said pole piece 64 yieldingly in a low position and permit the field pole to be raised by magnetic attraction when the relay is energized. The effect of said spring and consequently the current value for which the lower pole piece may be attracted upwardly may be varied by varying the strength of said spring as by varying the position of the check nut 67 on the adjusting rod 68.

The armature 61 may have its shaft 69 formed or provided with a worm thread 70 on the end thereof and said worm thread is adapted to engage a worm gear 71 of a speed-reducing mechanism. Said speed-reducing mechanism, including said worm gear, is or may be supported upon the pivoted lower pole 64 and the upward movement thereof serves to move said worm gear into mesh with the worm thread of said shaft 69, whereby said worm gear may be driven at a reduced speed by the armature 61. Said worm gear 71 may be formed or provided with a series of apertures 72 therein, which apertures may

be arranged concentrically with said gear. A movable circuit-controlling member is or may be arranged to be connected with said gear 71 by means of one of said apertures 72 whereby to be driven by said worm gear. Said circuit-controlling member may include the arms 73, which arms may be disposed on opposite sides of said worm gear 71 and be pivotally supported on the shaft 74 of said worm gear. Said arms 73 may extend beyond the periphery of said worm gear and the ends thereof may be connected by the insulating circuit-controlling bar 75, which bar preferably extends laterally on opposite sides of said arms. A screw 76 may be extended removably through one of said arms 73 and into one of said apertures 72, whereby to secure said arms adjustably in driving connection with said worm gears. Contact-members 77 and 78 may be secured to said frame 60 and one of said contact-members, as the contact-member 78, may extend into the path of movement of said insulating circuit controlling bar 75. The arrangement is or may be such that, as said armature 61 is rotated with its shaft in driving engagement with the worm gear 71, said circuit-controlling bar 75 is moved relatively slowly upward in a position to engage the contact member 78 and thereby move it to either make or break the circuit including said contact-members as may be desired. When the circuit is broken, the lower pole piece 64 of the relay is adapted to be moved downward by the spring 66 and in the position shown in Fig. 2, thereby to cause the disengagement of the armature 61 and the worm gear 71. The circuit controlling member is adapted to fall or rotate rapidly by gravity into its original or contact-free position. The angular relation between the circuit-controlling member and the contacts 77 and 78, as determined by the particular aperture 72 in which the pin or screw 76 of the circuit-controlling member is in engagement, determines the time period between the successive controls of the circuit including said contact members.

The relay so far described may constitute the reclosing relay as above mentioned. The disconnecting relay above mentioned may include the structure of the reclosing relay and, in addition, means to provide a slower rate of motion of the circuit-controlling member. The speed-reducing mechanism may include a small gear 80 fixed to the shaft 74 of the worm gear 71. Said gear 80 may mesh with a large gear 81 carried by the pivoted frame which includes the lower pole piece 64. Said gear 81 may be fixed to a small gear 82 and said small gear may be in mesh with a large gear 83, which large gear is or may be rotatably supported on the shaft 74 of the worm gear 71. Said gear 83 may be formed or provided with a series of apertures 72' therein, which apertures may correspond in manner

and function to the apertures 72 in the worm gear 71. A screw 76' may be disposed to enter in one of said apertures 72' and be threaded in an extension 73' of one of the arms 73 of the circuit-controlling member whereby said member will be driven at the speed of said gear 83, which speed may be reduced considerably over that provided by its direct connection with the worm gear 71.

The disconnecting relay is or may be also so arranged that it serves to control a second pair of contact-members 85 and 86 which contact-members are adapted to be biased to closed position but normally held open. For this purpose, said gear 83 may be formed or provided with the lateral extension or pin 87 and said pin is adapted to be rotated beneath and engage the contact-member 85 and thereby raise it from engagement with the contact-member 86 and said action preferably occurs when the disconnecting relay has been reversed to its normal reset position. When the circuit-controlling member is rotated forwardly toward the other contact-members 77 and 78, said contact-member 85 will be released and engage its cooperating contact 86 and thereby complete the circuit including said contact members.

The reclosing relay A, Fig. 1, is arranged with normally open contact-members 77 and 78 and said members are arranged, when closed, to bridge the manually-operable closing switch 47 and connect the hesitating relay to the auxiliary buses 30 and 31, the current passing from the bus 30 through the hesitating relay 48, conductors 49 and 90 and closed contact-members 78 and 77 to conductor 91 and 51 and thence to the other auxiliary bus 31. The two field coils 63 and 65 and the armature 61 of the reclosing relay are or may be connected in shunt and are arranged to be energized from the auxiliary buses when the main switch 10 is opened and de-energized when said switch is closed. As arranged for this purpose, the current may pass from the auxiliary bus 30 through the conductor 93, the stationary contacts 21 and the bridging contact 16 of the auxiliary switch, the conductor 94, the field coils and armature of the reclosing relay and thence through conductor 95, the armature 61 of the disconnecting relay B, and through the normally-closed contact-members 77 and 78 of said disconnecting relay and through the conductor 96 to the auxiliary bus 31. It is thus apparent that each time the main switch 10 is opened automatically, as by an overload, the reclosing relay A will operate to close its normally open contact-members 77 and 78 and effect the re-closing of the main switch. When said main switch 10 is closed, the auxiliary switch will be moved to break the circuit at the contacts 21 and thereby permit the reclosing relay to be reset. This action, if not gov-

erned by the disconnecting relay B, may continue indefinitely.

The disconnecting relay B is adapted to be energized each time the re-closing relay A is energized and move its circuit-controlling member towards its normally closed contact-members 77 and 78 thereby to open them and disable the reclosing relay A. The rate of movement of the circuit-controlling member of said disconnecting relay B, however, is adapted to be relatively slow as compared to the rate of movement of the circuit-controlling member of the reclosing relay so that a number of reclosing operations of the reclosing relay A may be carried out before the disconnecting relay B has been actuated sufficiently to disable the reclosing relay; and the particular number of operations permitted of the reclosing relay A may depend upon the particular settings of the circuit-controlling members of both relays.

The disconnecting relay B is also arranged to be positively rotated reversely when the main switch 10 is closed whereby to effect the resetting of said relay; and when the circuit-controlling member of said relay B has been restored to its normal position, the contact-members 85 and 86 are adapted to be opened whereby to prevent further reverse rotation of the relay.

In carrying out these features, one of the field coils of the disconnecting relay B, as the field coil 63, is arranged to be so connected as to rotate the armature of the disconnecting relay toward the contact-members 77 and 78. The other field coil 65 of said relay is adapted, when the main switch 10 is opened, to be energized to rotate the armature in the reverse direction and thereby reset the relay. As here shown, but one of the field coils is energized at a time, although the armature 61 is energized when the main switch 10 is opened and also when it is closed, providing the disconnecting relay has not separated the contacts 85 and 86. When the main switch 10 is open, the circuit is completed through the field coil 63 and the current passes in series through the armature and field coils of the re-closing relay A, the conductor 95, through the field coil 63, the conductor 98, the stationary contact members 23 and the bridging contact member 17 of the auxiliary switch, the conductor 99, the contacts 77 and 78 of said disconnecting relay and the conductor 96 to the auxiliary bus 31. It will be seen that the reclosing and disconnecting relays are arranged in series and that the armature of the disconnecting relay is arranged always in shunt with one of the field coils of the relay.

It will be apparent that when the armature of the disconnecting relay has been rotated forwardly for a sufficient period of time, the circuit-controlling member thereof will have been moved into a position to effect the sep-

aration of the contacts 77 and 78, and the de-energization of the armature and field coil, and also the de-energization and disabling of the reclosing relay, whereby to leave the main switch 10 in open position. As thus arranged, the disconnecting relay will maintain its contact-members 77 and 78 separated and consequently the reclosing relay will be disabled and the main switch 10 will remain in open position until it is reclosed manually or by the operation of the manually-controlled closing switch 47.

When the main switch 10 is reclosed manually it is desirable, at the same time, to reset or restore the disconnecting relay to its normal position, or as shown in Fig. 1. Inasmuch as the armature circuit of the disconnecting relay is interrupted through the contact-members 77 and 78 of the disconnecting relay V, an auxiliary circuit is provided, and said auxiliary circuit is or may be arranged normally to bridge said open contact-members 77 and 78. Said auxiliary circuit is controlled by the auxiliary switch of the main switch 10 and said circuit is adapted to be closed when the main switch is closed manually. Said auxiliary circuit extends from the contact-member 77 of the disconnecting relay through the conductor 101 and the fixed contact-members 24 and bridging member 17 of the auxiliary switch, and through conductor 102 and the fixed contact-members 22 and bridging contact-member 16 of the auxiliary switch, and thence through conductor 103 to the other contact member 78 of the disconnecting relay, and finally to the bus 31. When the main switch 10 is closed, therefore, the circuit through the armature 61 includes the resetting coil 65 and contact members 85 and 86 and the current passes from the auxiliary bus 30 through the conductor 105 to the contact-member 86 thence to the contact-member 85, conductor 106, fixed contact-members 26 and movable bridging members 18 of the auxiliary switch of the main switch 10, conductor 107, armature 61 and through the auxiliary circuit including the conductors 101 and 103 to conductor 96 and thence to the auxiliary bus 31. The resetting field coil 65 is connected across the armature 61 of the disconnecting relay through the circuit including the conductors 110 and 111, fixed contact-members 24 and bridging members 17 of the auxiliary switch of the main switch 10 and conductor 101. As thus arranged, the circuit is completed through the armature 61 and the resetting field coil 65 of the disconnecting relay and said armature is caused to rotate in the reverse sense and reset or restore the circuit-controlling member thereof to normal or contact-free position. When the circuit-controlling member arrives in normal position the contact-members 85 and 86 are separated thereby to interrupt the motor circuit

and stop the motor from further reverse rotation. The circuits which govern the forward rotation of the disconnecting relay are not effected by the above-described control of the contact-members 85 and 86 and the relay may be forwardly rotated in the manner previously described.

The operation of the system as above described may be substantially as follows:

When the main switch 10 is opened under overload, the reclosing relay A is caused to rotate to close its contact-members 77 and 78 and effect the reclosing of the switch. During the rotation of the reclosing relay, the disconnecting relay B is also caused to rotate in a forward direction or to open its normally-closed contact-members 77 and 78. Due to the fact that the reclosing relay A is arranged to move its circuit-controlling member at a higher speed than that of the disconnecting relay, the reclosing relay is adapted to effect the closing of the main switch 10. The reclosing relay is thereupon de-energized and the circuit controlling member falls by gravity to its normal position. When the main switch is in closed position, the disconnecting relay is caused to be rotated in a reverse sense and, if the main switch 10 stays closed by reason of the disappearance of the overload, the disconnecting relay may finally rotate into a position illustrated in Fig. 1 and remain inoperative in such position as against further reverse rotation. If, however, the short circuit still persists on the line governed by the main switch 10, said switch will be again opened and reclosing relay A will again operate to reclose the main switch and disconnecting relay B will be rotated forwardly as before. If the main switch is opened and closed repeatedly by reason of the continued overload on the line, the disconnecting relay will tend to rotate reversely each time the switch is closed. It may be, however, that, by reason of the short period of time the main switch is closed, before it again opens, and also by reason of the inertia or the moving parts of the disconnecting relay, said relay may remain without substantial reverse rotation even though it is energized for reverse rotation. After the reclosing relay has been operated a predetermined number of times, as determined by the respective settings of the two relays, the disconnecting relay B will have been rotated forwardly sufficiently to cause the separation of its normally closed contact members 77 and 78; and the disconnecting relay will become de-energized and maintain said contact-members separated and thereby disable the reclosing relay and consequently maintain the switch 10 open until it is manually closed.

It is to be noted that the act of reclosing the main switch serves automatically to effect the resetting of the reclosing system. The resetting field coil 65 of the disconnect-

ing relay may have different characteristics from that of the other field coil 63 whereby the disconnecting relay may be rotated reversely or in a resetting direction at a speed which is different from its speed in a forward direction.

The operation of the switch under the overload in its circuit and under the control of the associated relays may be termed its duty cycle.

10 The arrangement may be otherwise modified without departing from the spirit of the invention.

I claim:

15 1. An automatic reclosing system for an electric switch comprising means to open the switch upon overload, means rendered effective by the opening of the switch to reclose it repeatedly against the overload, and means to hold the switch open after a number of such reclosing operations, each one of said last two means having provision for varying the number of reclosing operations of the switch prior to its being held open independently of 20 the other of said two means.

25 2. An automatic reclosing system for an electric switch comprising means to open the switch upon overload, means to close the switch including a reclosing relay which is actuated during all the time that the switch is open to close it after it has been open a predetermined time, and means including a disabling relay which is operable independently of said reclosing relay and is rendered effective by the initial opening of the switch to move uninterruptedly throughout the time said switch is open toward a position to ultimately disable said reclosing relay and leave the switch open, said disabling relay having 30 self-disabling means, whereby to disable the system until reset.

3. An automatic reclosing system for an electric switch comprising means to open the switch upon overload, means including a reclosing relay rendered effective by the opening of the switch to close it repeatedly, said reclosing relay including switch-controlling contact-members, a movable controlling member movable into controlling relation with 45 said contact-members, speed-reducing gearing connecting said controlling member and actuating means, actuating means for said controlling member, and means to vary the time period of control of said contact-members by said controlling member, means including a disconnecting relay rendered effective by the initial opening of the switch to ultimately disable said reclosing relay and leave the switch open, said disconnecting relay having contact-members arranged to control the operation of said reclosing relay, a 50 controlling member for said contact members, actuating means for said controlling member, speed-reducing gearing connecting 55 said actuating means and controlling mem-

ber, and means to vary the time period of control of said contact-members by said controlling member.

4. An automatic reclosing system for an electric switch comprising means to open the switch upon overload, a reclosing relay rendered effective by the opening of the switch to close the switch repeatedly, said reclosing relay having a relatively fast-moving switch-closing member, a disconnecting relay rendered effective by the initial overload opening of the switch to disable said reclosing relay after a number of reclosings of the switch and leave the switch open, said disconnecting relay having a relatively slow-moving controlling member for said reclosing relay, whereby to permit said reclosing relay to close the switch repeatedly under overload prior to being disabled, and both relays having means to vary their time periods of 80 operation.

5. An automatic reclosing system for an electric switch comprising means to open the switch upon overload, means to close the switch including a reclosing relay rendered effective by the opening of the switch to reclose it repeatedly, and means including a disconnecting relay rendered effective by the initial opening of the switch to ultimately disable said reclosing relay and leave the switch 90 open, said disconnecting relay including contact-members arranged to control said reclosing relay, a control-member for said contact members arranged to be driven positively into a contact-controlling position and also positively into a contact-free position, means to drive said controlling member toward a contact-controlling position when the switch is open, and means to drive said controlling member toward a contact-free position when 95 the switch is closed, and means including other contact members controllable by said controlling member arranged to arrest said controlling-member in a contact-free position.

6. An automatic reclosing system for an electric switch comprising means to open the switch upon overload, means to close the switch including a reclosing relay rendered effective by the opening of the switch to reclose it repeatedly, and means including a disconnecting relay rendered effective by the initial opening of the switch to ultimately disable said reclosing relay and leave the switch open, said disconnecting relay including contact-members arranged to control said reclosing relay, a control-member for said contact members arranged to be driven positively into a contact-controlling position and also positively into a contact-free position, means to drive said controlling member toward a contact-controlling position when the switch is open, means to drive said controlling member toward a contact-free position when the switch is closed, means to arrest said controlling-member in a contact-controlling po- 100 110 115 120 125 130

sition, whereby to disable the system and leave the switch open, manually-controlled means to reclose the switch and return said controlling-member to a contact-free position, and means including other contact-members engageable with said controlling-member to arrest said controlling-member in contact-free position.

7. An automatic reclosing system for an electric switch comprising means to open the switch upon overload, means to close the switch including a reclosing relay which is actuated during all the time that the switch is open to close it after it has been open a predetermined time, and means including a disconnecting relay rendered effective by the initial opening of the switch to ultimately disable said reclosing relay and leave the switch open said disconnecting relay including contact-members arranged to control said reclosing relay, a controlling-member for said contact-members, means to move said controlling-member with delayed effect into a contact-controlling position including an actuating coil, means to move said controlling-member with delayed effect into a contact-free position including a re-setting coil, means rendered effective when the switch is open to energize said actuating coil, and means rendered effective when the switch is closed to energize said resetting coil.

8. An automatic reclosing system for an electric switch comprising means to open the switch upon overload, means to close the switch including a reclosing relay which is actuated during all the time that the switch is open to close it after it has been open a predetermined time, and means including a disconnecting relay rendered effective by the initial opening of the switch to ultimately disable said reclosing relay and leave the switch open, said disconnecting relay including contact-members arranged to control said reclosing relay, a controlling member for said contact-members, means to move said controlling-member with delayed effect into a contact-controlling position including an actuating coil, means to move said controlling-member with delayed effect into a contact-free position including a resetting coil, means rendered effective when the switch is open to energize said actuating coil, means rendered effective when the switch is closed to energize said resetting coil, and means governed by said controlling-member in contact-free position to de-energize said resetting coil.

9. An automatic reclosing system for an electric switch comprising means to open the switch upon overload, means to close the switch including a reclosing relay which is actuated during all the time that the switch is open to close it after it has been open a predetermined time, and means including a disconnecting relay rendered effective by the

initial opening of the switch to ultimately disable said reclosing relay and leave the switch open, said disconnecting relay including contact-members arranged to control said reclosing relay, a controlling member for said contact-member, means rendered effective when the switch is open and including an electric motor arranged to move said controlling-member with delayed effect into a contact-controlling position, whereby to disable said reclosing relay and leave the switch open, means rendered effective when the switch is closed to reverse the direction of rotation of said motor and move said controlling-member with delayed effect into a contact-free position, and means to de-energize said motor with said controlling-member in contact-free position.

10. An automatic reclosing system for an electric switch comprising means to open the switch upon overload, means to close the switch including a reclosing relay which is actuated during all the time that the switch is open to close it after it has been open a predetermined time, and means including a disconnecting relay rendered effective by the initial opening of the switch to ultimately disable said reclosing relay and leave the switch open, said disconnecting relay including contact-members arranged to control said reclosing relay, a controlling-member for said contact-members, and means to move said controlling-member with delayed effect into a contact-controlling position and also into a contact-free position comprising an electric motor, said motor having a rotatable armature arranged in driving relation with said controlling member, and two field coils therefor, means rendered effective by the open condition of the switch to energize the armature and one field coil, whereby to drive said controlling-member into contact-controlling position and disable said reclosing relay and means rendered effective by the closed condition of the switch to energize the armature and the other field coil, whereby to reverse the direction of rotation of the armature and drive the controlling-member toward a contact-free position, and means governed by said controlling-member in contact-free position to de-energize said motor.

11. An automatic reclosing system for an electric switch including means to open the switch upon overload, means rendered effective by the opening of the switch to reclose it repeatedly, and means movable continuously toward an operative position when the switch is open to ultimately render said reclosing means inoperative and to hold the switch open.

12. An automatic reclosing system for an electric switch, comprising means to open the switch upon overload, means to close the switch including a reclosing relay which is

actuated during all the time that the switch is open to close it after it has been open a predetermined time, and means including a second relay which is operable independently of said reclosing relay and is energized when the switch is open to move to a position to ultimately disable said reclosing relay and leave the switch open and also is energized when the switch is closed to move away from disabling position.

10 In testimony whereof, I have signed my name to this specification.

GEORGE W. O'KEEFFE.
